UNITED STATES PATENT OFFICE

LEONARD R. CARLEY, OF WATERTOWN, CONNECTICUT

DESIGN FOR A BUTTON

Application filed March 30, 1933. Serial No. 47,639. Term of patent 14 years.

To all whom it may concern:

Be it known that I, LEONARD R. CARLEY, a citizen of the United States, residing at Watertown, in the county of Litchfield and State of Connecticut, have invented a new, original, and ornamental Design for Buttons, of which the following is a specification, shown. reference being had to the accompanying drawing forming part thereof, in which:

Fig. 1 is a top plan view of a button on an enlarged scale showing my new design; Fig. 2 is a side elevation thereof; and Fig. 3 is a bottom plan view thereof.

I claim:

The ornamental design for a button, as

LEONARD R. CARLEY.
